United States Patent Office

Des. 192,421
Patented Mar. 20, 1962

192,421

TRACTOR SEAT

Harold W. Bostrom, Milwaukee, Wis., assignor to Bostrom Corporation, Milwaukee, Wis., a corporation of Wisconsin

Filed Dec. 6, 1960, Ser. No. 63,136

Term of patent 14 years

(Cl. D15—8)

FIG.

FIG. 2

Des. 192,421

PAGE 3

FIG. 3

FIG. 4

Fig. 5

FIGURE 1 is a top plan view of a tractor seat according to this design;

FIGURE 2 is a front elevation of the seat;

FIGURE 3 is a side elevation of the seat;

FIGURE 4 is a vertical section as indicated by line 4—4 in FIGURE 2; and

FIGURE 5 is a front perspective view of the seat.

The side of the seat not shown is the same as the side shown in FIGURE 3, and the back of the seat is substantially plain and unornamental.

I claim:

The ornamental design for a tractor seat as shown in the drawings, and as described.
